Patented Jan. 11, 1972

222,835

ARTIFICIAL CORSAGE

Gladys F. Rowland, 1327½ N. Hayworth Ave.,
Los Angeles, Calif. 90046

Filed June 10, 1970, Ser. No. 23,429

Term of patent 14 years

Int. Cl. D11—04

U.S. Cl. D29—1

FIG. 1

Des. 222,835

PAGE 2

FIG. 2

FIG. 1 is a front elevational view of my artificial corsage, showing my new design;

FIG. 2 is a view with the flower blossom slightly rearranged; and

FIG. 3 is a rear elevational view of FIG. 1.

I claim:

The ornamental design for an artificial corsage, as shown.
